United States Patent Office

Des. 214,346
Patented June 3, 1969

214,346

TYPEWRITER

Carl L. Otto, New York, N.Y., assignor to Litton Business
Systems, Inc., New York, N.Y., a corporation of New
York

Filed Sept. 30, 1968, Ser. No. 13,794

Term of patent 14 years

Int. Cl. D18—01

U.S. Cl. D64—11

Fig. 1

Fig. 3

FIGURE 1 is a perspective view illustrating the front of a typewriter embodying my new design;

FIGURE 2 is a perspective view illustrating the rear and right side of the typewriter shown in FIGURE 1; and

FIGURE 3 is a perspective view illustrating the front and left side of the typewriter shown in FIGURE 1 and FIGURE 2.

I claim:

The ornamental design for a typewriter, substantially as shown.
